CLAIM

The ornamental design for a TV receiver, as shown and described.

DESCRIPTION

1. TV receiver

1.1 is a front perspective view of a TV receiver.

1.2 is a rear perspective view thereof.

1.3 is a front view thereof.

1.4 is a back view thereof.

1.5 is a left side view thereof.

1.6 is a right side view thereof.

1.7 is a top view thereof.

1.8 is a bottom view thereof.

1.9 is a front perspective view of the TV receiver shown in an alternate position.

1.10 is a rear perspective view thereof.

1.11 is a front view thereof.

1.12 is a back view thereof.

1.13 is a left side view thereof.

1.14 is a right side view thereof.

1.15 is a top view thereof.

1.16 is a bottom view thereof.

The broken lines shown in the figures depict portions of the TV receiver that form no part of the claimed design.
